(57) **CLAIM**

The ornamental design for a combined electric toothbrush charger base and handle, as shown.

DESCRIPTION

FIG. 1 is a front perspective view of a combined electric toothbrush charger base and handle showing my new design.

FIG. 2 is a front view thereof;

FIG. 3 is a rear view thereof;

FIG. 4 is a right side view thereof;

FIG. 5 is a top view thereof; and,

FIG. 6 is a bottom view thereof.

The broken lines are for illustrative purposes only and form no part of the claimed design.
